FIG. 2

FIG. 3

FIG. 1 is a front-elevational view of a reflector incorporating my new design;

FIG. 2 is a top-plan view of the reflector of FIG. 1; and

FIG. 3 is a rear-elevational view of the reflector of FIG. 1.

The cross-hatching in FIG. 1 which is partially shown for convenience of illustration represents retroreflective elements which are visible over all of the areas on which they are partially indicated. The cross hatching is divided into three areas to signify that the inclination of elements in one area differs from that in the other areas.

I claim:
